TIME CONTROLLED SYSTEM

Edward B. Jackson, Downers Grove, Ill., assignor
to Stromberg Electric Company, Chicago, Ill.,
a corporation of Delaware

Application October 15, 1934, Serial No. 748,314

12 Claims. (Cl. 58-24)

The present invention relates in general to time controlled systems and more particularly to systems in which a plurality of secondary apparatuses are operated and controlled by a primary or master clock and in which each secondary apparatus is periodically corrected and synchronized with the master clock.

The main object of the invention is to provide a system of the above type which is exceedingly simple and reliable and which requires only one source of current and a two-wire control circuit between the master clock and the secondary apparatus.

According to one feature of the invention, all of the operating impulses transmitted by the master clock, both for normally operating and for accelerating the secondary apparatus, are of the same kind of current, are of the same intensity, and are all transmitted over the control circuit in the same direction.

According to another feature of the invention, a device is provided in each secondary apparatus which operates to open the circuit to the operating magnet when the secondary apparatus reaches a predetermined chronological position.

Another feature of the invention relates to the manner in which the above device is maintained in operated or locked position until released by the master clock when it reaches a corresponding chronological position.

According to a further feature of the invention, a relatively weak current is maintained in the control circuit during the synchronizing period to maintain inoperative such secondary apparatus as has been stopped in the predetermined chronological position.

The above and other objects and features of the invention not specifically mentioned above will best be understood from a perusal of the following specification when read in connection with the accompanying drawing, in which

Figure 1 is a schematic circuit diagram showing one embodiment of the invention; and

Fig. 2 is a schematic diagram showing a modified form of the invention.

Referring to the drawing in detail, the master apparatus 1 shown in Fig. 1 comprises any usual or suitable minute impulse contact device 1 for sending out the usual minute impulses to the secondary; any usual or suitable corrective rapid impulse contact device 2 for periodically sending out a series of rapid impulses to the secondary apparatus, (for example, one every two seconds over a period of thirty seconds) a contact device 3 controlled by master apparatus time for peri-

odically cutting in and out the rapid impulse contact device 2 (for example, from fifty-nine minutes and fifteen seconds to fifty-nine minutes and forty-five seconds), a relay 4 for controlling all of the impulses sent out by the master apparatus, a resistance 5 for enabling a continuous weak current to be supplied periodically to the line from the master apparatus to the secondary apparatus (for example, from fifty-five minutes to sixty minutes), and a contact device 6 controlled by master clock time for periodically cutting in and out the weak current supply resistance.

The secondary apparatus of Fig. 1 comprises any usual or suitable driving magnet 7, a ratchet and pawl mechanism 8 driven by the driving magnet 7, a small weak current magnet 9 for holding open the circuit of the driving magnet 7 when the secondary apparatus has reached a certain chronological condition, and a circuit controlling device 10 controlled by secondary apparatus time for opening the circuit for the driving magnet 7 and establishing a circuit for the weak current holding magnet 9 for holding its armature 11 in attracted position.

The circuits for the master apparatus shown comprise a circuit for the minute impulse contact device 1 and relay 4, a circuit for the rapid impulse contact device 2, and a circuit for the resistance 5.

The circuit for the minute impulse contact device 1 and relay 4 is from the source of current 12 through the conductor 13, magnet coils 14, conductors 15 and 16, minute impulse contact device 1 and conductors 17, 18 and 19 to the other side of the current supply 12. The circuit for the rapid impulse contact device 2 is from the conductor 18 through the rapid impulse contact device 2, conductor 20 and cam-controlled cut-out contacts 21 to the conductor 18. The circuit for the weak current supply resistance 5 is from the conductor 19 through the cam-controlled cut-out contacts 22, conductor 23, resistance 5 and conductor 24 to the conductor 25 leading to the secondary apparatus.

The circuit controlling device 10 of the secondary apparatus of Fig. 1 comprises a rockable spring contact 26 which in one position opens the circuit for the driving magnet 7 and establishes a circuit for the weak current holding magnet 9 and in another position opens the circuit for the weak current holding magnet 9 and re-establishes the circuit for the driving magnet 7, a rock arm 27 rockable with this contact 26 and with the arm 28 on which the armature 11 for the weak current holding magnet 9 is mounted,

and a spring dog 29 pivotally mounted on an arm 30 which carries the armature 31 for the driving magnet 7. This pivoted spring dog 29 is normally prevented from engaging the actuating arm 27 of the contact 26 by means of a circular disc 32 on the shaft 33 of the driven ratchet 34 but is enabled to engage this actuating arm in a certain position of the secondary apparatus when the notch 35 in the circular disc 32 comes opposite the pin 36 on the pivoted dog 29. In this position, the pin 36 on the pivoted dog 29 enters the notch 35 in the circular disc and in so doing engages the end of the actuating arm 27, opening the circuit for the drive magnet 7 and closing the circuit for the weak current magnet 9.

The circuits for the secondary apparatus of Fig. 1 comprise a circuit for the driving magnet 7 and a circuit for the small weak current magnet 9.

The circuit for the driving magnet 7 is from the line conductor 25 through the conductor 37, oscillatable contact 26, contact 38, conductor 39, magnet 7 and conductors 40 and 41 to the other line conductor 42. The circuit for the weak current magnet 9 is from the conductor 37, through the contacts 26 and 43, conductor 44, magnet 9 and conductor 41 to the line conductor 42.

In operation, the repeating relay 4 is energized once each minute by the momentary closure of minute contact 1, and at contacts 45 connects the battery or other source of current 12 to the conductors 25 and 42 extending to the secondary apparatus. These minute impulses pass through the secondary magnets 7 and operate the associated apparatus step by step.

Each time magnet 7 is energized, the dog 29 rocks on its pivot 46, since the pin 36 strikes against the periphery of the disc 32. When the secondary apparatus is in position 58, the notch 35 in disc 32 lies opposite the pin 36 on dog 29, so that when the next impulse energizes magnet 7, the pin 36 will enter the notch 35.

Referring now to the master clock circuit, at approximately five minutes, or any other desired time, before the master clock reaches position 60, contacts 22 are closed by cam 47, thereby connecting the resistance 5 across the impulsive contacts 45 of relay 4. The resistance 5 is made sufficiently high so that the continuous current which flows over the circuit during the synchronizing period is insufficient to interfere with the release of the secondary magnets 7, but is sufficient to hold up the small relays 9 once they are operated. Contacts 22 are opened shortly before (for example, ten seconds) the master clock reaches position 60. Contacts 21 are closed after the fifty-ninth impulse has been sent out and are again opened before contacts 22 are opened. While contacts 21 are closed rapid accelerating impulses are transmitted to the secondary apparatus by the fast contacts 2.

The continuous weak current which is maintained in the circuit from five minutes before the hour until ten seconds before the hour, as assumed for the purpose of explanation only, does not interfere with the regular advancing operations of the secondary apparatus by the master clock. During this time, the regular minute impulses and the fast accelerating impulses are sent out by the operation of relay 4 in the regular manner. At each impulse contacts 45 close, thereby connecting the full potential of the current source 12 to the line and bringing about the operation of the secondary magnets. When

the contacts open at the end of each impulse, the magnets release since the current through resistance 5 is insufficient to maintain them operated.

It will be assumed that the secondary apparatus S2 is fast and reaches position 58 before the master clock. When the next impulse is received, magnet 7 operates and in this position the pin 36 on the dog 29 can enter the notch 35 in disc 32. In doing so, it mechanically operates the armature 11 of relay 9, thereby opening contacts 38 and 26 and closing contacts 26 and 43. In order to make sure that the armature 31 will complete its movement, it may be desirable that the contacts 38 and 26 should not be opened until the contacts 26 and 43 are closed. For this purpose the contacts 38, 26 and 43 may be of the "make-before-break" type, the contact 38 being biased to follow downwardly with the contact 26 until the contacts 26 and 43 are closed, after which the contacts 38 and 26 are opened by further movement of the contact 26. The opening of contacts 38 and 26 opens the circuit of magnet 7, allowing the magnet to release and advance the secondary apparatus into position 59. The closing of contacts 26 and 43 completes the locking circuit for relay 9 and this relay is now maintained in operated position by the continuous weak current on the line until released by the opening of contacts 22 in the master clock just before the master clock reaches position 60. The continued energization of relay 9 maintains the circuit to magnet 7 open so that the remaining regular impulses and the fast accelerating impulses do not affect apparatus S2 which remains in position 59.

Apparatus, such as S1, which is slow or on time will continue to be advanced by the regular minute impulses and by the rapid accelerating impulses, if slow, received during the fifty-ninth minute. When S1 reaches position 58, the notch 35 in disc 32 will be opposite the pin 36 on the dog 29. When the next impulse is received, contacts 38 and 26 will be opened and contacts 26 and 43 closed. This opens the circuit to magnet 7, which releases and advances S1 into position 59, and completes the locking circuit to relay 9, which is held operated by the sustained weak current. All the secondary apparatus is now held inoperative in position 59.

Shortly before the master clock reaches position 60, contacts 22 are opened, removing resistance 5 from the circuit and cutting off the weak current. Relays 9 accordingly release, opening their locking circuits at contacts 43 and again preparing the impulsive circuits to magnets 7 at contacts 38. When the master clock reaches position 60, the regular minute impulse is transmitted to these magnets, advancing the secondary apparatus into position 60 and into synchronism with the master clock. It should be stated that the pin 36 on the dog 29 can enter the notch 35 in the disc 32 only when the magnet 7 is energized with the apparatus in position 58. The relays 9, therefore, cannot be again operated until the succeeding synchronizing period.

It will be noted that the armatures of relays 9 and the associated contacts are mechanically operated when magnets 7 are energized with the secondary apparatus in position 58. This construction necessitates the location of the relay in the secondary apparatus adjacent to the magnet so that the necessary mechanical connections can be made to effect the above operation. In some cases, the space may be limited so that the

relay cannot be placed adjacent to the magnet and the mechanical operation of the relay armature cannot readily be accomplished. The modification shown in Figure 2 of the drawing was designed for cases in which space was limited as this modification permits the placing of the relay anywhere in the secondary apparatus and, if necessary, outside of the apparatus altogether.

The principle of operation of the circuit of Figure 2 is practically the same as that of Figure 1. The master clock M1 is identical in all respects with the master clock M of Figure 1. The armature levers 30 of the secondary magnets 7 are provided with pivoted dogs 29 which cooperate with discs 32 in the same manner as the corresponding parts in Figure 1. The manner of operating relays 9, however, is somewhat different.

The secondary apparatus of Fig. 2 comprises the driving magnet 7, a ratchet and pawl mechanism 8 driven by said driving magnet, a small weak current magnet 9 controlled by secondary apparatus time, capable of holding its armature in retracted position under the influence of the periodic suspended weak current from the master apparatus, a circuit-controlling device 48 controlled by the armature of the weak current magnet for opening the circuit of the driving magnet 7 and establishing a holding circuit for the weak current magnet 9, and a circuit controlling device 49 controlled by secondary apparatus time for insuring closing the circuit for the weak current magnet.

The circuit controlling device 48 controlled by the weak current magnet 9 comprises an oscillatable contact 50 mounted on the arm which carries the armature 51 of the weak current magnet 9 and movable from a position in which the circuit of the driving magnet 7 is closed and the holding circuit for the weak current magnet 9 is open to a position in which the circuit for the driving magnet 7 is open and the holding circuit for the weak current magnet 9 is closed.

The circuit controlling device 49, controlled by secondary apparatus time for insuring the closing of the circuit for the weak current magnet 9, comprises an oscillatable contact 52 movable into and out of engagement with contact 50 for initiating the energization of the weak current magnet 9, and an actuating arm 54 for this oscillatable contact 52 cooperating with the aforesaid spring-pressed pivoted dog 29.

The circuits for the secondary apparatus of Fig. 2 comprise a circuit for the driving magnet 7, a circuit for initially energizing the weak current magnet 9, and a holding circuit for maintaining the weak current magnet 9 energized.

The circuit for the driving magnet 7 is from the line conductor 35 through the conductors 55 and 56, magnet 7, conductor 57, contacts 58 and 59, and conductor 58 to the other line conductor 32.

The circuit for initially energizing the weak current magnet 9 is from the conductor 55 through the magnet 9, conductor 60, contacts 62 and 63, and conductor 61 to the conductor 58. The holding circuit for the weak current magnet 9 is from the conductor 55 through the magnet 9, conductor 63 and contacts 63 and 59 to the conductor 58.

When a fast secondary apparatus, such as S4, is in position 58 and its magnet 7 is energized by the next impulse, the pin 36 on the dog 29 enters the notch 35 in disc 32 and operates the lever 54. This closes contacts 52 and 53 which complete the circuit from the line through the winding of relay 9.

Relay 9 is operated by the current impulse and at contacts 58 and 59 opens the circuit to the secondary magnet 7 which releases and advances the secondary apparatus into position 59. The release of magnet 7 also opens contacts 52 and 53, thereby opening the original operating circuit of relay 9. This relay, however, is now held operated over its locking circuit including contacts 63 and 50 which were closed when the relay 9 operated. Relay 9 is held operated by the weak current maintained on the line during the synchronizing period as explained in connection with Figure 1.

Slow apparatus or apparatus on time, such as S3, will continue to be operated by the regular minute impulses and, if slow, by the rapid accelerating impulses transmitted from the master clock as previously explained. When S3 reaches position 58 and receives the succeeding impulse, contacts 52 and 53 are closed to bring about the operation of relay 9, the deenergization of the magnet 7 and the associated advance of the apparatus into position 59, and the locking up of relay 9 over contacts 50 and 63.

All of the secondary apparatuses are now in position 59. Shortly before the master clock reaches position 60, contacts 22 are opened, removing resistance 3 from the circuit and cutting off the weak current from the line. Relays 9 accordingly release and at contacts 50 and 52 again prepare the impulsive circuits to magnets 7. The regular impulse transmitted by the master clock when it reaches position 60 operates magnets 7 in the regular manner and at the end of the impulse the secondary apparatuses S3 and S4 are advanced into position 60 and into synchronism with the master clock.

Having described the invention, what is new and is desired to have protected by Letters Patent will be pointed out in the appended claims.

Claims:

1. In a secondary apparatus for use in a corrective time controlled system, an operating magnet and an armature lever therefor, means mechanically operated by said lever upon energization of said magnet when said apparatus is in a predetermined chronological position for opening the circuit of said magnet, and a second magnet for holding said last means in operated position independently of its operating means.

2. In a secondary apparatus for use in a time controlled system, an operating magnet and a circuit therefor, a contact in said circuit, mechanical means operated by energization of said magnet only when said apparatus is in a predetermined chronological position for opening said contact, and means independent of said magnet for maintaining said contact in open position.

3. In a secondary apparatus for use in a time controlled system, an operating magnet and a circuit therefor, a relay and a circuit therefor, circuit controlling means for opening said magnet circuit and for closing said relay circuit, mechanical means controlled by the operation of said magnet and dependent upon the chronological position of said secondary apparatus for operating said circuit controlling means, and means controlled by the energization of said relay for maintaining said circuit controlling means in operated position.

4. In a secondary apparatus for use in a time controlled system, clock mechanism, an operating magnet for advancing said mechanism, a relay for opening the circuit of said magnet, means controlled by said magnet and operative only

when said mechanism is in a predetermined chronological position for operating said relay, and means independent of said magnet and said operating means for maintaining said relay in 5 operated position.

5. In a secondary apparatus for use in a time controlled system, an operating magnet having an armature, a relay, contacts controlled directly by said armature and operative only upon energization of said magnet when said apparatus is in a predetermined chronological position for completing an operating circuit for said relay, and means controlled by said relay for opening the 10 circuit to said magnet and for closing a locking circuit to hold said relay operated when said contacts are opened by the deenergization of said magnet.

6. In a corrective time controlled system, master apparatus and secondary apparatus connected 20 by a two-wire control circuit, an operating magnet in said secondary apparatus connected to said circuit, means in said master apparatus for transmitting regular operating impulses and rapid accelerating impulses over said circuit to operate 25 said magnet to advance said secondary apparatus, means effective when said secondary apparatus reaches a predetermined chronological position for preventing continued advance thereof, and means in said master apparatus for 30 transmitting a sustained relatively weak current over said circuit to said secondary apparatus to maintain said last means effective.

7. In a corrective time controlled system, master apparatus and secondary apparatus connected 35 by a two-wire control circuit, clock mechanism in said secondary apparatus, means in said secondary apparatus responsive to impulses transmitted from said master apparatus over said circuit for advancing said clock mechanism, means 40 for preventing continued advance of said mechanism when it reaches a predetermined chronological position, and other means operated by said master apparatus over said circuit to maintain said preventing means effective, said maintaining means being released when said master apparatus reaches a corresponding chronological 45 position to again permit advance of said clock mechanism by received impulses.

8. A corrective arrangement for a time controlled system comprising master apparatus and secondary apparatus connected by a control circuit, means in said master apparatus for transmitting normal operating impulses and rapid accelerating impulses over said circuit and for 50 transmitting a relatively weak sustained current thereover for a period during which a plurality of said normal impulses and all of said accelerating impulses are transmitted, means in the sec- 55

ondary apparatus for periodically preventing continued advance thereof at a predetermined point in its cycle of operation, and means controlled by said sustained current for maintaining said last means effective.

9. In a corrective time controlled system, master apparatus and secondary apparatus connected by a two-wire control circuit, means for advancing said secondary apparatus responsive to impulses transmitted over said control circuit from 10 said master apparatus, means for preventing continued advance of said secondary apparatus when it reaches a predetermined chronological position, holding means for maintaining said last-named means effective, and means in said master apparatus for transmitting a relatively weak current over said control circuit to said secondary apparatus to maintain said holding means in operative position until said master apparatus reaches a corresponding chronological 15 position.

10. In a master clock for use in a corrective time controlled system, an outgoing two-wire control circuit, means for transmitting normal operating impulses over said circuit at one rate, 20 means for transmitting a number of accelerating impulses over said circuit at a greater rate, and means for transmitting a sustained relatively weak current impulse over said circuit during the time a plurality of said normal impulses and 25 all of said accelerating impulses are transmitted.

11. In a master clock for use in a corrective time controlled system, an outgoing two-wire control circuit, means for transmitting over said circuit a plurality of normal operating impulses 35 at regular intervals, means for transmitting a plurality of rapid accelerating impulses, during the interval between two of said normal impulses, and means for maintaining in said circuit a relatively weak continuous current for a period during 40 which a plurality of said normal impulses and all of said accelerating impulses are transmitted thereover.

12. In a master clock for use in a corrective time controlled system, an outgoing control circuit, a source of current, a pair of contacts for connecting said source of current to said circuit, means for closing said contacts to transmit a series of normal operating impulses at regular intervals and a series of rapid accelerating impulses between two of said normal impulses over 45 said circuit to said secondary apparatus, a resistance, and means for shunting said resistance across said contacts for a predetermined period during which a plurality of said normal impulses and all of said accelerating impulses are transmitted.

EDWARD E. JACKSON.
